WALLET OR SIMILAR ARTICLE

Frank G. Dobbs and Stephan H. Dobbs,
New York, N. Y.

Application November 14, 1950, Serial No. 12,987

Term of patent 7 years

(Cl. D87—3)

To all whom it may concern:

Be it known that we, Frank G. Dobbs and Stephan H. Dobbs, citizens of the United States, residing in the city of New York, Borough and county of Queens, State of New York and in the city of New York, Borough of Manhattan, county and State of New York, respectively, have invented a new, original, and ornamental Design for a Wallet or Similar Article, of which the following is a specification.

Reference is being made to the accompanying drawings, constituting a part hereof, wherein,

Fig. 1 is a plan view of a wallet or similar article, in unfolded open position, showing our new design; and

Fig. 2 is a perspective view thereof, in closed position.

The dominant feature of our design for a wallet resides in the specific decorative motif on the lower half thereof as shown in Fig. 1 in association with the Indian head on the upper half of the wallet as shown in Fig. 1.

We claim:

The ornamental design for a wallet or similar article, substantially as shown and described.

FRANK G. DOBBS.

STEPHAN H. DOBBS.
